TIE RACK

William Grant Williams, Anaheim, Calif.

Application June 8, 1945, Serial No. 598,241

1. Claim. (Cl. 211—105)

1

This invention relates to improvements in tie racks of the type disclosed in my prior Patent No. 2,367,253, issued January 16, 1945.

An object of the invention is to provide an improved tie rack consisting of a lazy tongs type of structure adapted to be mounted on a wall or suitable support and having crossed bars pivotally connected to each other by a novel, simple, and advantageous type of pivotal connection which will simplify the construction and assembly of a device of this character.

More specifically, an object of the invention is to provide a tie rack consisting of a plurality of cross bars pivotally connected to each other by a pivotal connection that can be assembled or disassembled only when the bars that are so connected assume an abnormal relationship to each other and to provide a means for limiting movements of the bars with relationship to each other during normal operation so that they cannot assume such abnormal positions wherein the structure could be disassembled.

Another object of the invention is to provide a tie rack of this type wherein the bars may be formed of transparent or semi-transparent material, such as plastic, and the pivotal connection between the bars is such as to not be readily discernible therethrough.

With the foregoing and other objects in view, which will be made manifest in the following detailed description and specifically pointed out in the appended claims, reference is had to the accompanying drawings for an illustrative embodiment of the invention, wherein:

Figure 1 is a view in side elevation of the improved tie rack embodying the present invention;

Fig. 2 is a sectional view taken substantially upon the line 2—2 upon Fig. 1;

Fig. 3 is a sectional view taken substantially upon the line 3—3 upon Fig. 2, illustrating in phantom lines thereon the position that one bar is forced to assume with relation to its companion bar to enable assembly or disassembly; and

Fig. 4 is a partial view in section taken substantially upon the line 4—4 upon Fig. 3.

Referring to the accompanying drawings wherein similar reference characters designate similar parts throughout, the general construction of the tie rack illustrated consists of a plurality of crossed bars 10 and 11 which are pivotally connected to each other adjacent their centers and adjacent their ends. These bars have arms 12 equipped with heads 13 extending laterally therefrom from adjacent the pivot points. The innermost bars 14 and 15 have laterally ex-

tending bosses or pins 16, see Fig. 2, formed thereon which are slidable in opposed grooves in a pair of opposed members 17 and 18 that are retained in assembled relationship by a mounting bracket 19 adapted to be fastened to a wall or other upright support such as by screws 20. One of the outermost bars 21 may be extended to provide a handle 22.

A feature of the present invention resides in the pivotal connection provided at the pivot points of the various bars. To this end some of the bars, such as bars 11 and 15, have at their pivot points shank heads 23 which have shanks 24. The heads may be shaped somewhat similarly to a conventional rivet head being dome-shaped in form and circular in plan. The shanks 24 are relatively short in length and are generally cylindrical in diameters somewhat smaller than the diameters of the head 23. In one direction, however, the shanks are narrower than elsewhere, this being provided by forming these shanks with one or more flat sides 25. I prefer to arrange the direction of the narrow dimension of the shank at approximately 60° to the length of the bar on which it is mounted.

The companion or opposed bar such as 10 or 14 has a laterally open socket formed therein which has a recess 26 of a size and shape to permit the head to readily pass therethrough. Adjacent this recess there is a slot which communicates therewith and which has its inner end 27 somewhat wider than its entrance 28. The inner end of the slot has a diameter equal to the diameter of the shank but the entrance 28 has a width somewhat smaller than the diameter and which is only equal to the small or narrow dimension of the shank as provided by the flat sides 25. I prefer to arrange the length of the slot at substantially right angles to the length of the bar on which it is formed. With the parts so formed and arranged, it will be appreciated that opposed bars 10 and 11 can be assembled together by causing them to assume an abnormal relationship as illustrated in Fig. 3. In this position, the shank 24 can be caused to slide through the entrance 28 if the entrance assumes the position shown in phantom lines with relation to the flat sides 25. After sliding the head into the socket thus provided by the recess 26 and slot on turning the bars relatively to each other to disalign the flat sides 25 from the entrance 28, it is impossible to pass the shank 24 out of the entrance 28. Thus, the bars may be pivotally connected to each other and the parts readily assembled by merely temporarily positioning the bars in an abnormal relationship

with respect to each other. When the bars have been assembled together with members 17, 18, and 19 it may be mounted on the wall or other supporting structure. The lengths of the members 17 and 18 and particularly the slots or grooves formed therein in which the pins 16 are slideable are such as to limit movements of the bars 14, 15, and consequently 10 and 11 under normal positions other than the abnormal position shown on phantom lines on Fig. 3. Consequently, as the tie rack is extended or collapsed it never assumes a position wherein the flat sides 25 on the shanks 24 are in alignment with the narrow entrance 28 of the slot. Therefore as long as the tie rack remains mounted on the wall or other supporting structure it is impossible to disassemble the tie rack by withdrawing the heads from their respective sockets.

I prefer to construct the improved tie rack of a transparent or semi-transparent material such as plastic, and in so doing, if the heads and shanks are formed of similar material and are cast integral with their respective bars the pivotal connections between the bars are not readily discernible through the material of which the bars are formed. Furthermore, in molding those bars on which the heads are formed if the parting line of the mold is arranged centrally of the bar and extending lengthwise thereof through the shanks, the arrangement is such that the halves of the mold can readily separate from the sides of the shank. The sockets on the companion bars must be cored out with a two-part core, one part of which may core out the recesses 26 and the entrances 28 of the slots, and the other part of which may core out the widened inner ends 27 of the slots. In this manner, the elements of the improved tie rack may be readily molded or cast from a material such as plastic and the parts readily assembled together; once that all of the parts are assembled and the tie rack is mounted

on a wall it is impossible during operation of the tie rack for the parts to reassume the abnormal position illustrated in phantom lines on Fig. 3, and thus become disassembled from each other.

Various changes may be made in the details of construction without departing from the spirit and scope of the invention as defined by the appended claim.

I claim:

10 A tie rack comprising a plurality of crossed bars pivotally connected together by shanked heads on certain bars laterally receivable in sockets in opposed bars, the shanks being narrower in one direction than otherwise with the narrower dimension only being receivable through the entrances to the sockets, and means for mounting said bars on a support so as to be collapsible and extensible with respect thereto, said means limiting relative pivotal movements of the bars to positions wherein the heads are incapable of being withdrawn from their respective sockets.
